UNITED STATES PATENT OFFICE.

JOHN GELZENLICHTER, OF LYNN, MASSACHUSETTS, ASSIGNOR TO MANUFACTURERS MACHINE COMPANY, OF MONTCLAIR, NEW JERSEY, A CORPORATION OF NEW JERSEY.

BUFFING-MACHINE.

No. 871,990.

Specification of Letters Patent.

Patented Nov. 26, 1907.

Application filed July 11, 1906. Serial No. 325,582.

To all whom it may concern:

Be it known that I, JOHN GELZENLICHTER, a citizen of the United States, residing at Lynn, in the county of Essex, State of Massachusetts, have invented an Improvement in Buffing-Machines, of which the following description, in connection with the accompanying drawings, is a specification, like letters on the drawings representing like parts.

10 This invention relates to buffing machines of the type commonly known as "Naumkeag" machines, used principally in the manufacture of boots and shoes.

In the manufacture of boots and shoes it is customary to buff or "grain" the bottoms of the fore parts with a buffing machine, employing a roll surrounded by an abradant covering, but this roll cannot be carried along the shanks to the heels, and for buffing 20 shanks machines of the Naumkeag type are employed, they having pads of disk shape that revolve about vertical axes. These Naumkeag pads permit of the buffing of the shanks of the shoes, however irregular in 25 shape they may be, and also, by reason of their circular shape, permit the buffing to be carried close to and to follow the usual curved breast lines of the heels.

Naumkeag machines are customarily employed for first buffing or graining of the shanks, and then, usually with a finer abradant, are used for finishing both the shanks and the fore parts.

Naumkeag machines have generally been 35 provided with pneumatic pads made of rubber and adapted to be inflated with air to give them a rounded shape and a highly resilient quality. These pads have been provided with coverings of emery cloth molded 40 to approximately the shape of the deflated pad, provided with in-turned, tongued lips or flanges adapted to overlie the pads and be clamped in position, so that when the pads are inflated to resume their full rounded position, the covers will be given the true pad shape for the first time. In applying these 45 pad covers it has been customary to provide machines with cover-applying devices located at one side and when re-covering has 50 been required the pads of necessity were removed, with their heads and parts of the carrying spindles therefor, and transferred to the cover applying devices to receive the

covers, after which they were replaced upon their spindles and the pads inflated for use. 55 All this has consumed time that could better have been employed by the parties in performing work on the machines for which they would receive pay.

My invention aims to improve the buffing 60 machine of the Naumkeag type in many respects calculated to facilitate the performance of work thereon.

To this end my invention, among other things, contemplates a pad cover applying 65 device which while mounted normally at one side and in position where it will not interfere with the performance of work on the machine may, when a new pad cover is to be applied, be moved or swung into position 70 directly in line and beneath the spindle carrying the pad to be covered so that the pad cover may be applied directly to the pad on the spindle without necessitating the removal of the pad or any part of the spindle, 75 with all the loss of time incident thereto.

My invention also contemplates a cover applying device that is capable of applying the pad cover already molded, full rounded or of the desired shape to the pad of full 80 rounded shape, either pneumatic or other, without necessitating the deflation or flattening thereof.

My invention contemplates various other features which together with those above 85 particularly referred to will be best understood from a description of the machine illustrating one embodiment thereof.

Fig. 1, in side elevation, shows a machine illustrating one embodiment of my 90 invention. Fig. 2, a detail in front elevation, showing a part of the machine head. Fig. 3, a detail in top or plan view, of the front part of the machine head on an average scale, this view showing the 95 normal and also the operative position of the cover applying device in the embodiment of my invention here shown. Fig. 4, a cross sectional detail on the dotted line 4—4, Fig. 3. Fig. 5, an enlarged plan view of the 100 cover applying device. Fig. 6, a detail in elevation partial section, of the cover applying device, this view showing the applying device in full lines, in normal position and in dotted lines in active position. Fig. 7, a 105 similar view showing the applying device in

the act of laying over the lip of the cover about and upon its pad. Fig. 8, a detail illustrating one form of cover that may be used.

5 In the particular embodiment of my invention selected for illustration herein and shown in the drawings, referring first to Fig. 1, the machine column 1, its head 2, provided at the front with a vertical spindle 3, carrying a pad 4, with a clamping cap 5, screwed thereon, said head being provided at its rear end with a pair of idler pulleys 6, over which a belt 7, extended about a pulley on the pad spindle may be carried in leading it down to 10 and about the driving pulley 8, on a drive shaft 9, at the base of the column, are or may be of any suitable desired construction so far as concerns my present invention.

15 The pad 4, may be of the Naumkeag type adapted to be inflated for use or, if desired and preferable, said pad may be of some composition or structure that will cause it normally to retain its desired shape without inflation yet preserving at all times the necessary elasticity or resiliency required for the 20 particular work for which these machines are adapted.

25 In machines of this type means is usually provided for drawing and conducting away the dust produced by the buffing, and while it is often preferred to connect the machine with the general exhaust dust system of the factory employing one single suction apparatus for all machines, it is also common to 30 provide each individual machine with its own suction fan. In the machine here illustrated the latter practice has been followed and the column, see Fig. 1, is shown provided with a fan chamber 10, provided 35 internally with a usual suction fan (not shown), and having an outlet at 11, adapted to be connected with any useful discharge conduit. The inlet conduit for this fan chamber leads upward and forward to a position directly behind and opposite the pad 4, said inlet being here indicated at 11^a. To facilitate bringing the pad applying device into operative position beneath the pad, the inlet end 11^a, of this suction conduit is made 40 movable, the same as here shown, being carried at one side the head upon a hinge 12, on an arm 13, projecting from the side of the machine head. This inlet has a lip 14, rising to a level above the pad, to facilitate the 45 entrance of dust to the inlet.

50 Referring now to Fig. 3, the same casting in which said movable inlet 11^a, is formed is shown provided with a laterally extended and downwardly directed arm 14^a, reaching through to the opposite side of the machine from that at which the hinge 12, is located, said arm at its outer end being provided with a vertical bearing for the stem 15, of the cover applying device A. This stem is 55 shown provided at its upper end with a spider

16, in the arms of which are provided at 17, a circular series of infolders 18, see Figs. 3 and 5. These infolders are broadened at their inner converging ends somewhat like a spade and are provided respectively with 70 depending fingers 19, which underlie the peripheral lip of the central actuator 20, see Fig. 6. This actuator at its upper side is cup shaped preferably to fit interiorly the 75 desired operating shape of the pad to which the cover is to be applied, said cup shaped actuator being mounted upon the upper end of the spindle 21, arranged to slide vertically within the stem 15, made tubular for the purpose. The actuator spindle is supported 80 within said stem by a spring 22, which, when the applying device as a whole is lifted, causes the actuator to be lifted with it, but which yields when the actuator meets the 85 opposite pad or cover thereon and holds the said cover against or about said pad while the further upward lifting movement of the stem, its spider, and the infolders thereon causes the latter, as indicated in dotted lines, Fig. 6, to be turned and moved radially inward about the actuator lip as a fulcrum to lay over the cover lip upon the upper edge of the pad. The cover is here indicated at 90 23, Fig. 8, and is preferably, as stated, molded to the desired shape before it is 95 placed over or against the pad. It may have any kind of clamping lip, but that here shown is wired or tongued as at 24, said lip being shown as first inturned somewhat and then its tongues are directed outwardly to 100 facilitate applying the cover to the pad without folding the tongues under and between the cover and the pad.

105 Referring to Fig. 6, it will be clear how the cover may be placed loosely in position upon the pad and the cover applying device A raised to cause its actuator 20, to inclose the cover and press it smoothly against the fully shaped or rounded pad after which the infolders are moved to infold the tongue or 110 other lip of the cover over and upon the pad periphery as shown in full lines Fig. 7. Infolders are then slightly withdrawn by dropping the applying device and the clamping cap 5, screwed down upon and to hold firmly 115 the inturned lip or tongues thereon, after which the device may be restored to its lowermost position.

120 To facilitate lifting of the applying device I have provided the same with a bearing hand lever 25, see Fig. 6, fulcrumed at 26, on the end of the arm 14, and having its forked end entering a vertical slot in the stem 15, to receive a pin 27, passing therethrough. This handle is directed outwardly into position 125 convenient for engagement by the operator and furnishes sufficient power for the applying device conveniently and to smoothly and effectually apply a cover to the pad above it.

130 The side of the stem 15 is shown as notched

at 28, for engagement by a spring pressed latch 29, adapted to catch the same in the most elevated position to which it is brought and there hold it and the cover while the 5 clamping cap 5, is being adjusted in clamping position. After the cover has been applied, this latch is released and the applying device dropped and swung back to normal position.

10 The applying device and suction inlet 11^a, being upon one and the same casting and thus connected, as the one is moved into position relative to the spindle the other is correspondingly moved out of position to give 15 clearance thereto.

In Fig. 6 the infolders 18, are shown as presenting a lost motion between themselves and the actuator lip 20, and there shown as normally supported from beneath by springs 20 30, which however are capable of yielding during the action of the infolders upon a cover. The effect of these springs is intended to be to hold the infolders in a more elevated position than would normally be the 25 case by the lip alone yet giving them the advantage of a downward play during the infolding motion, which a rigid lip would not permit.

Referring to Fig. 7, the actuator 20, is 30 seated and restrained from rotation by two guide rods 31, reaching downward through the spider to and through guides on the arm head 14^a.

To assist bringing the applying device into 35 perfect alinement with the spindle, I have provided the machine head, just back of the pad spindle with a spring pressed latch 32, see Fig. 4, adapted to be lifted against the action of its spring by a hand lever 33, ful- 40 crumed at 34, on the side head. The casting of which the suction inlet and carrying arm 14^a are a part, is provided with two recesses, one of which is shown in dotted lines, Fig. 3, and the other in full lines at 35, Fig. 3. The 45 former of these recesses receives the latch 32, and holds the inlet 11, in position during the normal operation of the machine. When the applying device is to be brought into action this handle 33 is depressed to lift its

50 latch and release the casting, when the latter may be turned on its hinge to bring the applying device into position beneath the pad where it is caught, centered and locked by the spring action of said lock 32, which 55 brings it into position until the pad cover has been applied, when said latch is again released and the parts restored to normal position.

Referring now to Fig. 5, I have shown the 60 infolders 18, as provided respectively with laterally extended ears 36, which enter respectively lateral slots or recesses in the next adjacent infolders. These ears constitute one form of closures for closing the spaces be- 65 tween the several infolders. Of course as the

infolders are withdrawn radially these intervening spaces widen and as they again converge when brought together for applying a pad cover there might at times be danger of crinkling or creasing the cover lip in the 70 process of infolding.

Directly below and in the rear of the pad is shown the usual brush 37, driven by a belt 38, from a pulley on the shaft of the idlers 6, and arranged in a suction hood 39, connected 75 with the suction of the machine and on which the surfacers buffed may be cleaned of dust.

It will be clear that the operation of changing or applying pad covers is greatly facilitated by my invention because no time is 80 lost in removing the pad carrier positioning it in the cover applying device, removing it from the applying device, positioning it on its spindle as heretofore. A single movement is sufficient to bring the applying device into position for applying a cover and a similar opposite movement to restore it to its normal inactive position. Furthermore and absolutely, the pad carrier is much less likely 85 to become loosened and incapable of use 90 when permitted to remain always upon its spindle than when it is required to be removed frequently,—in fact, many times each day, as heretofore, for the application of covers to the pad.

95 My invention is also advantageous because it insures the desired and proper formation of the cover when it is applied, because the shape given to the actuator 20, is of necessity communicated to the cover and thus determines predeterminedly the shape 100 of the operating surface of the cover.

While my invention is perhaps most applicable to a machine of the type here shown, it is however, applicable to any machine 105 having any sort of a pad or operative support for the abrasive covering in which my invention might be found useful.

I claim.

1. In a buffing machine, the combination 110 with a pad carrying support, of a cover applying device and means to move it toward and from said support, for use in applying a cover to the latter.

2. In a buffing machine, the combination 115 with a pad carrying spindle, of a pad cover applying device mounted in proximity to said spindle and movable into and out of operative position relative to and for assisting in applying a pad cover to a pad on said 120 spindle.

3. In a buffing machine, the combination 125 with a pad carrying support, of a transferable cover applying device, and means to transfer it to cover applying position.

4. In a buffing machine, the combination with a pad carrying support, of a transferable cover applying device, and means to center it in cover applying position and also in normal inoperative position.

5. In a buffing machine, the combination with a pad carrying support, of a pad cover applying device mounted in proximity to said support and transferable into and out 5 of applying position relative to said support, and operating means therefor transferable therewith.
6. In a buffing machine, the combination with a pad cover support, of a pad cover applying device having cover applying means presenting substantially the shape of the cover when in operative condition.
7. In a buffing machine, the combination with a cover support, of a cover applying device comprising a yielding face presser and infolding means coöperating therewith.
8. In a buffing machine, the combination of infolders 18, a support 16 therefor, an actuator 20 for said infolders, and means for 20 moving the actuator and infolders.
9. In a buffing machine, the combination with a cover support, of a cover applying device comprising a yielding face presser, infolding means coöperating therewith, and 25 means for transferring said applying device to and from said cover support.
10. In a buffing machine, the combination with a cover support, of a face former to give desired formation to the cover face, infolding 30 means coöperative therewith, and means for transferring said applying device to and from said cover support.
11. In a buffing machine, the combination of infolders 18, a support 16 to which they 35 are pivoted, an actuator 20 having a part engaging said infolders, and means for relatively moving the actuator and infolders.
12. In a buffing machine, the combination with a pad carrying spindle and means to rotate it, of a cover applying device normally 40 out of operative relationship with a pad on said spindle but transferable into operative relationship therewith, and means to operate said applying device in its said operative position.
13. A buffing machine provided with a cover applying device expandible and contractible radially and means to move the same axially to produce said radial movement.
- 50 14. A buffing machine provided with cover applying means contractible and expandible radially and an axially movable actuator therefor.
15. A buffing machine provided with cover 55 applying means contractible and expandible radially and an axially movable face forming actuator therefor.
16. A buffing machine provided with cover applying means contractible and expandible 60 radially and an axially movable and yielding actuator therefor.
17. In a buffing machine, the combination with a buffing device of a suction conduit therefor and a cover applying device, said conduit and applying device being selectively movable into and out of operative relationship to said buffing device. 65
18. In a buffing machine, the combination with a buffing device of a suction conduit therefor and a connected cover applying device, said conduit and applying device being selectively movable to carry one into and the other out of operative relationship to said buffing device. 70
19. In a buffing machine, the combination with a buffing device of a suction conduit therefor and a connected cover applying device, both selectively movable into and out of operative relationship to said buffing device, said conduit and cover applying device 80 being respectively hinged for connected movement into and out of position. 75
20. In a buffing machine, the combination with a buffing device of a cover applying device transferable into and out of operative 85 position relative to said buffing device, means for moving said cover applying device transversely to its transferring movement, and locking means to retain it in its transversely moved position. 90
21. A buffing machine comprising, in combination, a pad, cover affixing means therefor, a suction conduit the inlet of which is movable into and out of effective relation to said pad and means connecting said affixing 90 means and conduit inlet such that as one is moved into operative relation to said pad the other is moved out of such relation.
22. In an apparatus of the character described, the combination with infolders 18, a support 16 to which they are movably connected, an actuator 20 having a part engaging said infolders, and means for conjointly moving the actuator and infolders to place the cover against the pad and to thereafter 105 relatively move the infolders and actuator to fold the edge of the cover about the pad. 100
23. In an apparatus of the character described, the combination of infolders 18, having recessed ends, a support to which 110 said infolders are pivoted, an actuator 20 having a part engaged by the recessed ends of the infolders, means for moving the infolders and actuator together to bring the cover into engagement with the pad, and 115 yielding means to permit relative movement of the infolders and actuator.
- In testimony whereof, I have signed my name to this specification, in the presence of two subscribing witnesses.
